UNITED STATES PATENT OFFICE

126,874

DESIGN FOR AN AUTOMOBILE

Frederic W. Plumb, West Reading, Pa.

Application January 9, 1940, Serial No. 89,360

Term of patent 3½ years

To all whom it may concern:

Be it known that I, Frederic W. Plumb, a citizen of the United States, residing at West Reading, in the county of Berks and State of Pennsylvania, have invented a new, original, and ornamental Design for an Automobile, of which the following is a specification, reference being had to the accompanying drawing, forming part thereof.

Fig. 1 is a side elevational view of an automobile, showing my new design.

Fig. 2 is a plan view, and Figs. 3 and 4, are respectively front and rear end elevational views, of the same.

Fig. 5 is a top perspective view thereof.

I claim:

The ornamental design for an automobile, as shown.

FREDERIC W. PLUMB.
